UNITED STATES PATENT OFFICE.

HARRY H. BRIDGWATER AND JONATHAN HALEY, OF AKRON, OHIO,
ASSIGNORS TO THE AKRON GLASS AND MACHINERY COMPANY,
OF AKRON, OHIO, A CORPORATION OF OHIO.

UNLOADING AND CONVEYING APPARATUS.

No. 800,622.

Specification of Letters Patent.

Patented Oct. 3, 1905.

Application filed April 18, 1904. Serial No. 203,718.

To all whom it may concern:

Be it known that we, HARRY H. BRIDGWATER and JONATHAN HALEY, citizens of the United States of America, residing at Akron, 5 in the county of Summit and State of Ohio, have invented certain new and useful Improvements in Unloading, Loading, and Conveying Apparatus; and we do hereby declare the following to be a full, clear, and exact description 10 of the invention, such as will enable others skilled in the art to which it pertains to make and use the same.

This invention relates to improvements in unloading, loading, and conveying apparatus, and pertains more especially to apparatus of the character indicated wherein carriages are mounted upon and movable along a track and during the travel of a carriage along the said track if the carriage is unladen 15 the following occurs: First, a rack arranged at an elevation above the track and normally at one side of the track and capable of being swung in a horizontal plane to and over the track is swung into position over the track 20 by the operation of mechanism controlled by the moving unladen carriage which is to be loaded from the rack; second, the rack is automatically locked upon swinging the rack into its unloading position over the track; 25 third, any ware borne by the rack is delivered onto the carriage; fourth, the carriage having been laden renders the means employed in locking the rack in its unloading position inoperative and permits the rack to be swung into its normal position ready to receive another load, and the laden carriage 30 moves along the track to the desired destination.

The object of this invention is to provide 40 apparatus of the character indicated wherein a carriage already laden will pass by the movable ware-conveying rack without resulting in the actuation of the rack; but an unladen carriage will in moving along the track 45 preparatory to its passage by the rack actuate mechanism operatively connected with the rack, and thereby effect the actuation of the rack into its unloading position, wherein any ware upon the rack is removed from the rack 50 onto the carriage by ware-removing members with which the carriage is provided.

Another object is to render the apparatus

simple and durable in construction and reliable in its operation.

With these objects in view this invention 55 consists in certain features of construction and combinations of parts hereinafter described, and pointed out in the claims.

In the accompanying drawings, Figure 1 is a top plan of a track and unloading, loading, 60 and conveying apparatus embodying our invention, and portions are broken away in this figure to reduce the size of the drawing. Fig. 2 is a top plan illustrating the attachment to each other of two adjacent sections of the 65 track at the meeting ends of the said sections. Fig. 3 is a side elevation relative to Fig. 2. Fig. 4 is a transverse vertical section on line 4 4, Fig. 3, looking in the direction indicated by the arrow. Fig. 5 is a top plan of a portion of the apparatus and shows, among other things, the stationary rack A and a traveling 70 ware-conveying carriage having members in position to remove ware from the said rack onto the carriage. Fig. 6 is a side elevation, 75 largely in section, on line 6 6, Fig. 5, looking in the direction indicated by the arrow. Fig. 7 is a transverse vertical section on line 7 7, Fig. 6, looking in the direction indicated by the arrow. Figs. 8, 9, 10, and 11 are top 80 plans of portions of the apparatus. Fig. 9 illustrates the movable rack B in its ware-receiving position, and Fig. 8 shows a carriage 25 in position to commence operating means employed in actuating the movable 85 rack into its ware delivering or unloading position, and portions are broken away and in section in Fig. 8 to more clearly show the construction. Figs. 10 and 11 are illustrative 90 of the actuation of the movable rack into its unloading position. Fig. 12 is a section on line 12 12, Fig. 10, looking in the direction indicated by the arrow. Fig. 13 is a section on line 13 13, Fig. 10, looking in the direction indicated by the arrow. Fig. 14 is a section on line 14 14, Fig. 12, looking in the direction indicated by the arrow. Fig. 15 is a section on line 15 15, Fig. 11, looking in the direction indicated by the arrow. Fig. 16 is a section corresponding with Fig. 15, except 95 that in Fig. 16 a jar *w* is shown having been carried by a carriage 25 from over the ware-receiving seat of the movable rack. Fig. 17 is a top plan in section on line 17 17, Fig. 16.

Our improved apparatus comprises a suitably-supported endless track T, which is arranged in a horizontal plane at the desired elevation. The track T extends (see Fig. 1)

- 5 past two racks A and B, from which ware or articles are to be conveyed to a distant point adjacent another portion of the said track. The track T adjacent the last-mentioned point extends around a sprocket-wheel 10 R', operatively mounted on a suitably-supported vertically-arranged shaft R², which is operatively provided below the said wheel with a driving-wheel R³, to which power is suitably applied. The racks A and B are 15 stationary and movable, respectively. The track T adjacent the stationary rack A extends around a sprocket-wheel R⁸, which is supported in any approved manner. The track T is provided with suitable bends, if required, as shown at C.

The track T to facilitate the building and any subsequent lengthening, shortening, or change in trend of the same is made in sections 20, assembled endwise, with adjacent track-sections arranged in line longitudinally, as shown in Figs. 2 and 3. Preferably adjacent track-sections 20 are provided at their meeting or adjacent ends with depending horizontally-arranged ears 22, clamped together in any approved manner—as, for instance, by a suitably-applied bolt D and nut d, as shown in Figs. 2, 3, and 4. An endless chain or carrier R operatively engages the sprocket-wheels R' and R⁸ and lies in a channel 25 t, formed in and centrally widthwise of the track T. The channel t extends longitudinally of the track. The chain R is arranged on edge—that is, with the pivotal connection R⁴ between adjacent links of the chain arranged vertically, so as to render the chain readily capable of passing around the sprocket-wheels. The chain R is guided in any approved manner between the wheels R' and R⁸—as, for instance, by suitably-applied sprocket-wheels 30 R⁵, supported from the track T. The inner portion of the track T is cut away, as at t², adjacent the sprocket-wheels R' and R⁸, as shown in Fig. 1. The track T is provided at the sides with upwardly-projecting flanges t', 35 which extend longitudinally of the track and are arranged to form side guides for the ware-conveying carriages 25, mounted upon the track and arranged at suitable intervals longitudinally of the track, which carriages are attached to the chain R.

To enable adjacent track-sections 20 to participate in mutually supporting each other at their adjacent ends and to prevent displacement of each of the said sections at the said 40 ends independently of the other of the said sections, one of the said sections is provided at each side of its channel t and exteriorly with a vertically-arranged ear 23, projecting between two correspondingly-arranged ears 45 24, formed upon the other of the said sections,

and the interlocking ears 23 and 24 of the said sections at each side of the track are also but not necessarily secured together by a suitably-applied bolt E and nut e.

The carriages 25 are obviously propelled by the chain R during the actuation of the chain. Each carriage 25, as shown very clearly in Figs. 5, 6, 7, 8, 10, 12, 13, and 14, comprises a body portion r, which is attached to the chain R in any approved manner and rests upon the track T at the sides of the channel t. Each carriage 25 comprises also a platform u, which is pivotally mounted on the body portion r of the carriage, being pivoted, as at u', horizontally to and transversely of the said body portion. The platform u of each carriage 25 is arranged horizontally upon the body portion r of the carriage; but the forward portion of the platform—that is, the platform forwardly of its axis—is weighted, as at 50 26, (see Figs. 6, 12, 13, and 14,) and will tip downwardly whenever permitted to do so. The said platform u is provided with several vertically - arranged upwardly - projecting flanges u², which extend longitudinally of and 55 from end to end of the platform. The body portion r of each carriage 25 is provided rearward of but in close proximity to the rear end of the platform of the carriage with two upwardly-projecting arms or members 27, arranged a suitable distance apart widthwise of the platform. (See Figs. 5, 6, 7, 8, 10, and 12.)

The stationary rack A is arranged in the main over the track T, as shown in Figs. 1, 5, 6, and 7, and the ware-receiving seat a of the said rack is arranged at an elevation at and slightly above the path of the platforms u of the carriages 25, as shown in Figs. 6 and 7. The seat a is provided with slots a², which extend from end to end of the seat and are arranged to accommodate the location of the flanges u² of the platform u of a carriage 25 during the propulsion of the said carriage along and past the said seat to receive a piece of ware or article to be unloaded from the rack A onto the said platform. The chain R is propelled and actuated in the direction indicated by the arrow marked upon the track T, and the rack A at the rear end of the seat a comprises a web a', which connects the different portions of the seat a together and permits of the provision of a seat a, having the slots a².

In Figs. 5, 6, and 7 a jar w is shown placed upon the seat a, and a carriage 25 is in position to receive the said jar from the said seat—that is, Figs. 5, 6, and 7 show the ware-removing arms or members 27 of the said carriage in engagement with the said jar. The web a' of the rack A is slotted vertically, as at 28, to accommodate the location of the arms or members 27 of the carriages 25, and the arms or members 27 of the platform u of each carriage 25 are arranged such a distance apart laterally that during the propulsion of

the said carriage they come simultaneously into engagement with the jar or article *w*, to be thereby removed from the rack A, and thereupon shove the said jar or article from off the seat *a* of the said rack in the direction in which the said carriage is being propelled and result in the delivery of the said ware or article onto the said platform. The rack A is provided at a suitable elevation above the seat *a* with two horizontally-arranged guard-forming arms 30, which project in the direction in which ware placed upon the said seat is to be removed from the rack and are located at opposite sides, respectively, of the rack in position to prevent displacement of ware placed upon the rack laterally in opposite directions, respectively. The rack A is provided at the bottom with two arms or brackets 32, depending from the seat *a* at opposite sides, respectively, of the path of the carriages 25, as shown very clearly in Fig. 7, which brackets or arms are rigidly secured in any approved manner to the track T.

The primary object of this invention is not only to convey ware or articles from the stationary rack A, but also to convey ware or articles from the movable rack B, arranged at any suitable point between the rack A and the destination of the ware or articles to be conveyed from the said racks. The rack B thus arranged intermediately between the stationary rack A and the destination of the ware to be conveyed is movable into and out of position over the track T.

The rack B is shown very clearly in Figs. 9, 11, 14, 15, 16, and 17. The rack B substantially corresponds in construction with the stationary rack A, already described. The rack B has a ware-receiving seat *b*, which is arranged at an elevation at and slightly above the path of the platforms *u* of the carriages 25 when the said platforms are laden. The seat *b* is provided with slots *b*², which extend from end to end of the seat and are arranged to accommodate the location of the flanges *u*² of the platform *u* of a carriage 25 during the propulsion of the said carriage along and past the said seat to receive a piece of ware or article to be unloaded from the rack B onto the said platform when the said rack is in position to deliver—that is, over the track T. The rack B at the rear end of the seat *b* comprises a web *b*', which connects the different portions of the seat *b* together and permits the provision of a seat *b*, having slots *b*². In Figs. 9, 11, 14, and 15 a jar *w* is shown placed upon a seat *b*. In Fig. 9 the rack B is shown in its ware-receiving position. In Figs. 11, 14, and 15 the rack B, laden with a jar *w*, is shown swung into its ware delivering or unloading position over the track T. In Figs. 8, 10, 12, 13, and 14 a carriage 25 is shown approaching the rack B. In Figs. 16 and 17 a jar *w* is shown delivered to a carriage 25 from the rack B. Prepara-

tory to the removal of a jar *w* from the rack B onto a carriage 25 the ware-receiving arms or members 27 of the said carriage come into engagement with the said jar the same as already described during the removal of a jar 70 from the stationary rack A. The web *b*' of the rack B is slotted vertically, as at 38, to accommodate the location of the arms or members 27 of the carriages 25. The rack B is provided at a suitable elevation above the seat *b* with two horizontally-arranged guard-forming arms 35, which project in the direction in which ware placed upon the said seat is to be removed from the rack and are located at opposite sides, respectively, of the rack in 80 position to prevent displacement of ware placed upon the rack laterally in opposite directions, respectively.

To render practicable the conveying of ware from the racks to a destination in common, 85 the movement of the movable rack B into its ware delivering or unloading position is controlled by a carriage 25, which is unladen, and a carriage 25, already laden with a jar *w* or piece of ware delivered thereon from the stationary rack A, moves past the movable rack B without resulting in the actuation of the said movable rack; but a carriage 25, passing to the rack B and not having received a jar *w* or ware from the rack A, shall at the proper 95 time effect the movement of the rack B into its unloading position over the track T.

The means employed in effecting the actuation of the rack B into its ware delivering or unloading position comprises (see Figs. 1, 100 8, 9, 10, 11, 13, and 14) an endwise-shiftable bar G, arranged horizontally and externally of and extending along the track T, which bar has bearing in two boxes 34, rigid with the track and arranged a suitable distance apart 105 longitudinally of the track. The bar G is located between the racks A and B and provided at its outer side and centrally between its ends with a laterally-projecting arm 36, whose outer longitudinal edge has the trend required to 110 form an incline *g*, which faces laterally and toward the rack B. The trend of the incline *g* is therefore inwardly and toward the rack B from the outer and free end of the arm 36. The rack B is arranged a suitable distance 115 forwardly of the forward end of the bar G, and a lever H, instrumental in swinging the said rack in a horizontal plane from its outer and ware-receiving position into its inner and unloading position, extends longitudinally of 120 the outer side of the said bar and is fulcrumed vertically and centrally between its ends, as at 37, to a bracket 39, which is formed upon and projects laterally from the track T below the said bar. The movable rack B is secured 125 at its web *b*' to the forward end of the lever H. The lever H is provided at its rear end with a vertically-arranged roller *h*, which in the normal position of the rack B—that is, when the said rack is in its ware-receiving 130

position—is arranged in engagement with the inner end of the incline g of the bar G , as shown in Figs. 1, 8, and 9. It is obvious, therefore, that when the bar G is actuated—
 5 that is, in the direction of the rack B —the incline g of the said bar will swing the lever H in the direction required to move the rack into its ware delivering or unloading position over the track T . In Figs. 1 and 9 the rack B is shown in its ware-receiving position and bears a jar w . In Figs. 11, 14, and 15 the rack B is shown in its unloading position over the track T . The lever H during its actuation by the incline g moves against the action of a suitably-applied weight I , which is shown in Figs. 9, 11, and 14. The weight I acts, therefore, to retain the rack B in its normal or ware-receiving position. The weight I is suspended by a cable J , which is attached to
 10 the forward or rack-bearing end of the lever H and leads over a guide-sheave 40, which is supported from an arm or bracket 42, which is rigid with and projects laterally from the track T . The bracket or arm 42 has an up-
 15 per track-forming surface engaged by a roller 43, with which the forward and rack-bearing end of the lever H is provided. The bracket or arm 42 is arranged substantially concentrically of the axis of the lever H , so that the
 20 roller 43 will remain in engagement with the track formed by the said arm during the actuation of the said lever. A suitably-applied weight K acts to retain the bar G in its rear-
 25 ward and normal position. The weight K is suspended by a cable h , which is attached to the outer or free end of the arm 36 of the bar G and leads over a guide-sheave 44, supported from the outer end of an arm or bracket 45, which is rigid with and projects laterally
 30 from the track T .
 The track T is provided adjacent the bar G and rearwardly of the fulcrum 37 of the lever H and at each side of the channel t of the track with a depression T' , which extends longitudinally of the track, and the poise or downward extension 26 of the forward end of the platform u of each carriage 25 has the dimensions required to cause the forward portion of the said platform when the platform is un-
 35 laden to tip downwardly by gravity into the track depressions T' during the passage of the said carriage over the said depressions, as shown very clearly in Figs. 8, 10, 12, 13, and 14. The forward end walls T' of the de-
 40 pressions T' slope upwardly and forwardly, so as to gradually lift the downwardly-tipped forward and heavier end of the unladen platform u of the carriage during the passage of the carriage from over the said depression.
 45 The jar or ware w to be conveyed by a carriage 25 is carried upon the rear portion of the platform u of the said carriage, and the weight of the load upon the rear portion of the laden platform is sufficient to prevent the

forward portion of the said platform from tipping downwardly during the passage of a laden carriage over the depressed portion of the track T .

The bar G is provided at or near its arm 36 with a rearwardly-facing shoulder 50, (see Figs. 8, 10, 13, and 14,) which shoulder is arranged to be engaged by a pin or member 52, which is rigid with and projects laterally from the platform u of an unladen carriage approaching the rack B —that is, the bar G is provided with a shoulder 50, which is arranged in the path of a pin or member 52 of the platform u of an approaching carriage 25 when the said platform is unladen. It will be observed, however, as shown in dotted lines, Fig. 13, that the pin or member 52 of the platform u of the carriage when the said platform has been lifted from the track depression T' is arranged high enough to enable the said member 52 to pass over and past the bar G , and obviously, therefore, a laden platform will pass over and past the said bar without coming into engagement with the shoulder 50 of the bar.

The forward end walls T' of the track depressions T' are arranged forwardly of the shoulder 50 of the bar G , and the arrangement of the parts is such, therefore, that the platform u of each carriage 25 which is unladen will during the passage of the said carriage to and over the track depressions T' during the propulsion of the carriage tip downwardly at its forward and heavier end into the said depressions, so as to bring the pin or projecting member 52 thereof forward of the shoulder 50 and result in the engagement of the said shoulder by the said pin or projecting member of the platform, and hence result in the forward actuation of the bar G against the actuation of the weight K and in the swinging of the rack B into its ware delivering or unloading position against the action of the weight I . The shoulder 50 is arranged substantially concentrically of the axis of the platform u , so that upward displacement of the forward and heavier end of the platform u during the engagement of the shoulder 50 by the pin or member 52 of the said platform is positively prevented until the platform is again lifted out of the track depressions T' by the sloping forward end walls T' of the said depressions. The arrangement of the parts is such, furthermore, that the rack B shall have been swung into its ware-delivering position before the power-transmitting platform u has been lifted out of the track depressions T' , and the arm 36 at the outer end of its incline g is provided with a rearward extension 46, whose outer side edge is arranged parallel with the path of the bar G and is engaged by the roller h of the lever H during the actuation of the bar G while the power-transmitting platform u is ascending the slop-

ing end walls T² of the said track depressions until the member 52 of the said platform has disengaged the shoulder 50.

To lock the rack B in its ware delivering or unloading position and retain the same until the jar or ware thereon has been taken from the said rack and to automatically unlock the said rack when the jar or ware has been removed from the rack, the following is provided:

5 One of the arms 35 of the rack B (see Figs. 9, 11, 15, 16, and 17) is provided at its free end with a notch or recess 55, which extends vertically through and longitudinally of the said arm and is open at its outer end. The said 15 arm at the outer side of the said recess is provided with an incline 56, the trend whereof is inwardly and forwardly toward the free extremity of the said arm. The track T is provided with an upright latch L, which is pivoted 20 at its lower end horizontally and transversely of the track, as at 7. The latch L is arranged, therefore, to swing in a vertical plane and longitudinally of the track T. The latch L is provided at its lower end, above its axis, with 25 a forwardly-projecting arm 57, which is provided at its upper side and free end with an incline 58, which slopes upwardly and forwardly and is arranged in the path of a pin or laterally-projecting member r', with which the 30 body portion r of each carriage 25 is provided. The latch L is provided also at its lower end with a rearwardly-projecting arm 60, which carries a poise 62, normally resting upon an arm or bracket 63, which is rigid with and projects laterally from the track T. The poise 35 62 acts to retain the latch L in its normal position, in which the incline 58 of the latch is arranged, as already indicated, in the path of the members r' of the body portions r of the 40 carriages 25. The arrangement of the parts is such that the incline 56 of the rack B during the swinging of the said rack into its ware delivering or unloading position comes into engagement with the latch L and swings the 45 said latch forwardly against the action of the poise 62 until the recess 55 of the rack B has come opposite the said latch, whereupon the latch will be swung rearwardly by the action of the poise 62 into the said recess, and thereby 50 lock the said rack in its said unloading position. The arrangement of the parts is such, furthermore, that the pin or member r' of the body portion r of each carriage 25 will during 55 the propulsion of the said carriage not come into engagement with the incline 58 of the latch-arm 57 until the jar or ware w has been removed from over the rack B, as shown in Figs. 16 and 17, whereupon the said arm will be depressed by the passage of the said pin or 60 member r' over the incline 58, so as to result in the swinging of the latch L against the action of the poise 62 out of engagement with the recess 55 of the rack, and obviously the said rack as soon as unlocked by the disengagement of the latch L from the said recess 65

is swung by the action of the weight I into its normal and ware-receiving position.

A yielding stop arranged to limit the rearward movement of the bar G into its normal position is provided and consists, preferably, 70 of a spiral spring s, which is arranged longitudinally of and attached to the said bar and extends from within a recess 65, formed in the rear end of the bar a suitable distance beyond the said end of the bar, as shown in Figs. 8 75 and 11, and in the aforesaid position of the bar projects into a recess 66, formed in a lug 67, which is formed upon and projects from the track T.

What we claim is—

1. The combination, with a ware-conveying carriage, and means for actuating the carriage, of a ware-conveying rack normally in its ware-receiving position and movable into its unloading position; and means whereby the rack 85 is actuated into its unloading position by a moving unladen carriage.

2. The combination, with a ware-conveying carriage, and means for actuating the carriage, 90 of a ware-conveying rack normally at one side of the path of the carriage and movable laterally into its unloading position relative to said path, and means whereby the rack is actuated into its unloading position by an unladen carriage preparatory to the passage of the 95 carriage past the rack during the propulsion of the carriage.

3. The combination, with a ware-conveying carriage, and means for actuating the carriage, 100 of a ware-conveying rack normally at one side of the path of the carriage and adapted to be swung laterally into its unloading position relative to the said path, and means whereby the rack is swung into its unloading position by an unladen carriage preparatory to the 105 passage of the carriage past the rack during the propulsion of the carriage.

4. The combination, with a ware-conveying carriage, and means for actuating the carriage, 110 of a ware-conveying rack normally in its ware-receiving position and movable into its unloading position, of means acting to retain the rack in its normal position, and means whereby the rack is actuated into its unloading position by a moving unladen carriage. 115

5. The combination, with a ware-conveying carriage, and means for actuating the carriage, 120 of a ware-conveying rack normally in its ware-receiving position and movable into its unloading position, means whereby the rack is actuated into its unloading position by an unladen carriage, means for locking the rack in its unloading position, and means for rendering the rack-locking means inoperative.

6. The combination, with a ware-conveying 125 carriage, and means for actuating the carriage, of a ware-conveying rack normally at one side of the path of the carriage and movable into its unloading position relative to the said path, means acting to retain the rack in its 130

normal position, means whereby the rack is actuated into its unloading position by an unladen carriage preparatory to the passage of the carriage past the rack during the propulsion of the carriage, means for locking the rack in its unloading position, and means for rendering the rack-locking means inoperative.

7. The combination, with a ware-conveying carriage, and means for actuating the carriage, of a ware-conveying rack normally at one side of the path of the carriage and movable into its unloading position relative to the said path, means whereby the rack is actuated into its unloading position by an unladen carriage preparatory to the passage of the carriage past the rack during the propulsion of the carriage, means for locking the rack in its unloading position, and means whereby the said rack-locking means is automatically rendered inoperative by and during the propulsion of the carriage upon the delivery of ware from the rack onto the carriage.

8. In combination, a track, a ware-conveying rack normally in its ware-receiving position and movable into its unloading position relative to the track, a carriage engaging and movable along the track, means for propelling the carriage, and means whereby the rack is actuated into its unloading position by a moving carriage preparatory to the passage of the carriage past the rack during the propulsion of the carriage.

9. In combination, a track, a ware-conveying rack normally at one side of the track and movable into its unloading position over the track, a carriage engaging and movable along the track, means for propelling the carriage, and means whereby the rack is actuated into its unloading position by an unladen carriage preparatory to the passage of the carriage past the rack during the propulsion of the carriage.

10. In combination, a track, a ware-conveying rack normally at one side of the track and movable into its unloading position over the track, a carriage engaging and movable along the track, means for propelling the carriage, and means whereby the rack is actuated into its unloading position by a moving carriage preparatory to the passage of the carriage past the rack during the propulsion of the carriage, means for locking the rack in its unloading position to the track, and means for rendering the said rack-locking means inoperative.

11. In combination, a track, a ware-conveying rack normally at one side of the track and movable into its unloading position over the track, a carriage engaging and movable along the track, means for propelling the carriage, means whereby the rack is actuated into its unloading position by a moving carriage preparatory to the passage of the carriage past the rack during the propulsion of the carriage, means arranged to automatically lock the rack to the track upon actuating the rack into

its unloading position, and means whereby the said rack-locking means is automatically rendered inoperative by and during the propulsion of the carriage upon the delivery of ware from the rack onto the carriage.

12. In combination, a track, a ware-conveying rack normally in its ware-receiving position and movable into its unloading position, a carriage engaging and movable along the track, means for propelling the carriage, means acting to retain the rack in its normal position, means whereby the rack is actuated into its unloading position by a moving carriage, means for locking the rack to the track in the unloading position of the rack, and means for rendering the rack-locking means inoperative.

13. In combination, a track, a ware-conveying rack normally at one side of the track and movable into its unloading position over the track, which rack is provided, at one side, with a recess; a carriage engaging and movable along the track; means for propelling the carriage along the track; means acting to retain the rack in its normal position; means whereby the rack is actuated into its unloading position by a moving carriage preparatory to the passage of the carriage past the rack; a latch pivotally supported from the track and arranged to engage the aforesaid recess in the operative position of the latch when the rack is in its unloading position; means acting to retain the latch in its operative position, and means for rendering the latch inoperative.

14. In combination, a track; a ware-conveying rack normally in its ware-receiving position and movable into its unloading position relative to the track, which rack is provided with a recess; a carriage engaging and movable along the track; means for propelling the carriage; means acting to retain the rack in its normal position; means whereby the rack is actuated into its unloading position by a moving carriage preparatory to the passage of the carriage past the rack; a latch pivoted to and transversely of the track and arranged to engage the aforesaid recess in the operative position of the latch when the rack is in its unloading position, which latch is provided with an upwardly and forwardly sloping incline; means acting to retain the latch in its operative position, and the carriage being provided with a projecting member arranged to engage the incline, during the propulsion of the carriage, and swing the latch forwardly to disengage the latch from the aforesaid recess.

15. In combination, a track; a ware-conveying rack normally at one side of the track and movable into its unloading position over the track, which rack is provided, at one side, with a recess; a carriage engaging and movable along the track; means for propelling the carriage; means acting to retain the rack in its normal position; means whereby the rack is actuated into its unloading position by a

moving carriage preparatory to the passing of the carriage past the rack; an upright latch pivoted, at its lower end, to and transversely of the track and arranged to engage the aforementioned recess in its normal and operative position, which latch is provided, at its lower end, with a forwardly-projecting arm having an upwardly and forwardly sloping incline; means acting to retain the latch in its operative position, and the carriage being provided with a projecting member arranged to engage the incline during the propulsion of the carriage and thereupon render the latch inoperative.

16. The combination, with a track, and a ware-conveying rack normally in its ware-receiving position and movable into its unloading position relative to the track, of an endwise-shiftable bar arranged at one side and longitudinally of the track, which bar has a rearwardly-facing shoulder; means acting to retain the bar in its rear and normal position; means whereby the forward actuation of the bar results in the actuation of the rack into its unloading position; means acting to retain the rack in its normal position; a carriage movable along the track and comprising a body portion resting upon the track and a platform pivoted to and transversely of the body portion, which platform is heavier forwardly than rearwardly of its axis and provided, forwardly of its axis, with a projecting member arranged to pass over or engage the aforesaid shoulder according as the forward portion of the platform is untipped or tips downwardly, and means whereby the platform, when unladen, tips downwardly forwardly of its axis preparatory to the passage of the carriage past the rack during the propulsion of the carriage.

17. The combination, with a track, and a ware-conveying rack normally at one side of the track and movable into its unloading position over the track, of an endwise-shiftable bar arranged at one side and longitudinally of the track, which bar has a rearwardly-facing shoulder; means acting to retain the bar in its rear and normal position; means whereby the forward actuation of the bar results in the actuation of the rack into its unloading position; means acting to retain the rack in its normal position; a carriage movable along the track and comprising a body portion resting upon the track and a platform pivoted to and transversely of the body portion, which platform, forwardly of its axis, is weighted and provided with a projecting member arranged to pass over or engage the aforesaid shoulder according as the forward portion of the platform is untipped or tips downwardly, and means whereby the platform, when unladen, tips downwardly forwardly of its axis preparatory to the passage of the carriage past the rack during the propulsion of the carriage.

18. The combination, with a track, and a ware-conveying rack normally at one side of

the track and movable into its unloading position over the track, of an endwise-shiftable bar arranged at one side and longitudinally of the track, which bar has a rearwardly-facing shoulder; means acting to retain the bar in its rear and normal position; means whereby the forward actuation of the bar results in the actuation of the rack into its unloading position; means acting to retain the rack in its normal position; a carriage movable along the track and comprising a body portion resting upon the track and a platform pivoted to and transversely of the body portion, which platform, forwardly of its axis, is provided with a projecting member arranged to pass over or engage the aforesaid shoulder according as the forward portion of the platform is untipped or tips downwardly, and means whereby the platform, when unladen, tips downwardly forwardly of its axis preparatory to the passage of the carriage past the rack during the propulsion of the carriage, and the aforesaid shoulder somewhat sloping upwardly and over the aforesaid projecting platform member when the latter engages the said shoulder.

19. The combination, with a track and a ware-conveying rack arranged normally at one side of the track and movable into its unloading position over the track, of an endwise-shiftable bar arranged at one side and longitudinally of the track, which bar has a rearwardly-facing surface and is provided with a laterally and forwardly facing incline; means acting to retain the bar in its rear and normal position; a lever arranged alongside of the bar and fulcrumed centrally between its ends, which lever, at its forward end, carries the rack and, at its rear end, is normally arranged adjacent the inner end of and in position to be engaged by the incline in the normal position of the rack; means acting to retain the rack in its normal position; a carriage movable along the track and comprising a body portion resting on the track and a platform pivoted to and transversely of the body portion, which platform is provided, forwardly of its axis, with a laterally-projecting member arranged to pass over or engage the aforesaid rearwardly-facing surface of the bar according as the forward portion of the platform is untipped or tips downwardly, and means whereby the platform, when unladen, tips downwardly forwardly of its axis preparatory to the passage of the carriage past the rack during the propulsion of the carriage.

20. The combination, with a track and a ware-conveying rack arranged normally at one side of the track and movable into its unloading position over the track, of an endwise-shiftable bar arranged at one side and longitudinally of the track, which bar has a rearwardly-facing surface and is provided with a laterally and forwardly facing incline; means acting to retain the bar in its rear and normal position; a lever arranged alongside of

the bar and fulcrumed vertically between its ends, which lever, at its forward end, carries the rack and is provided, at its rear end, with an upright roller arranged adjacent the inner 5 end of the incline in the normal position of the rack; means acting to retain the rack in its normal position; a carriage movable along the track and comprising a body portion resting upon the track and a platform pivoted to 10 and transversely of the body portion, which platform is provided, at its forward end, with a laterally-projecting member arranged to pass over or engage the aforesaid rearwardly-facing surface of the bar according as the 15 forward portion of the platform is untipped or tips downwardly, and means whereby the platform, when unladen, tips downwardly forwardly of its axis preparatory to the passage of the carriage past the rack during the 20 propulsion of the carriage.

21. The combination, with a track having a depressed portion, and a ware-conveying rack normally at one side of the track forward of the depressed portion of the track and movable 25 into its unloading position over the track, and means acting to retain the rack in its normal position, of a lever bearing the rack and arranged at one side and extending longitudinally of the track, which lever is fulcrumed 30 rearward of the rack and arranged to swing in a horizontal plane; means acting to retain the lever in its normal position; an endwise-shiftable bar extending alongside and longitudinally of the track and having a rearwardly-facing surface, which bar is provided 35 with a laterally and forwardly facing incline arranged to actuate the lever during the forward actuation of the bar; means acting to retain the bar in its normal position; a carriage 40 comprising a body portion engaging the track and a platform pivoted to and transversely of the body portion, which platform is provided, forwardly of its axis, with a laterally-projecting member arranged to pass over or engage the aforesaid rearwardly-facing 45 surface according as the forward portion of the platform is untipped or tips downwardly, and means for propelling the carriage along the track, and the forward portion 50 of the platform having the dimensions required to enable it to tip downwardly into the depressed portion of the track during the propulsion of the carriage.

22. The combination, with a track having a 55 depressed portion, and a ware-conveying rack normally at one side of the track forward of the depressed portion of the track and movable into its unloading position over the track, and means acting to retain the rack in its normal position, of a lever bearing the rack and arranged at one side and extending longitudinally of the track, which lever is fulcrumed rearward of the rack; means for preventing 60 sagging of the rack-bearing portion of the lever; means acting to retain the lever in its 65

normal position; an endwise-shiftable bar extending alongside and longitudinally of the track and having a rearwardly-facing surface, which bar is provided with a laterally and forwardly facing incline arranged to actuate the lever during the forward actuation of the bar; means acting to retain the bar in its normal position; a carriage comprising a body portion engaging the track and a platform pivoted to and transversely of the body portion, which platform is provided, forwardly of its axis, with a laterally-projecting member arranged to pass over or engage the aforesaid rearwardly-facing surface according as the forward portion of the platform is 70 untipped or tips downwardly, and means for propelling the carriage along the track, and the forward portion of the platform having the dimensions required to enable it to tip downwardly into the depressed portion of the 75 track during the propulsion of the carriage.

23. The combination, with a track having a depressed portion, and a ware-conveying rack normally at one side of the track forward of the depressed portion of the track and movable 80 into its unloading position over the track, and means acting to retain the rack in its normal position, of a lever bearing the rack and arranged at one side and extending longitudinally of the track, which lever is fulcrumed 85 vertically rearwardly of the rack; means acting to retain the lever in its normal position; an endwise-shiftable bar extending alongside and longitudinally of the track and having a rearwardly-facing surface, which bar is provided 90 with a laterally and forwardly facing incline arranged to actuate the lever during the forward actuation of the bar; means acting to retain the bar in its normal position; a carriage comprising a body portion engaging 95 the track and a platform pivoted to and transversely of the body portion, which platform is provided, at its forward end, with a laterally-projecting member arranged to pass over or engage the aforesaid rearwardly-facing 100 surface according as the forward portion of the platform is untipped or tips downwardly, and means for propelling the carriage along the track, and the forward portion of the platform being heavier than the rear portion 105 of the platform and having the dimensions required to enable it to tip downwardly into the depressed portion of the track during the propulsion of the carriage.

24. The combination, with a track having a 110 depressed portion whose depression extends longitudinally of the track and has a forwardly and upwardly sloping forward end wall, and a ware-conveying rack normally at one side of the track forward of the depression in the 115 depressed portion of the track and movable into its unloading position over the track; means acting to retain the rack in its normal position, and a horizontally-swinging lever arranged longitudinally of the track, which 120

lever, forward of its axis, bears the rack; means acting to retain the lever in its normal position; an endwise-shiftable bar extending alongside and longitudinally of the track and having a rearwardly-facing surface, which bar is provided with a laterally and forwardly facing incline arranged to actuate the lever during the forward actuation of the bar; means acting to retain the bar in its normal position; a carriage comprising a body portion engaging the track and a platform pivoted to and transversely of the body portion, which platform is provided, forwardly of its axis, with a projecting member arranged to pass over or engage the aforesaid rearwardly-facing surface according as the forward portion of the platform is untipped or tips downwardly, and the forward portion of the platform having the dimensions required to enable it to tip downwardly into the aforesaid depression during the propulsion of the carriage.

25. The combination, with a track having a depressed portion whose depression extends longitudinally of the track, and a ware-conveying rack normally at one side of the track forward of the depression in the depressed portion of the track and movable into its unloading position over the track; means acting to retain the rack in its normal position, and

30. a horizontally-swinging lever arranged longitudinally of the track, which lever, forward of its axis, bears the rack; means acting to retain the lever in its normal position; an endwise-shiftable bar extending alongside and longitudinally of the track and having a rearwardly-facing surface, which bar is provided with a laterally and forwardly facing incline arranged to actuate the lever during the forward actuation of the bar; means acting to

35. retain the bar in its normal position; a yieldable stop arranged to limit the rearward movement of the bar; a carriage comprising a body portion engaging the track and a platform pivoted to and transversely of the body

40. portion, which platform is provided, forwardly of its axis, with a projecting member arranged to pass over or engage the aforesaid rearwardly-facing surface according as the forward portion of the platform is untipped

or tips downwardly, and the forward portion 50 of the platform having the dimensions required to enable it to tip downwardly into the aforesaid depression during the propulsion of the carriage.

26. The combination, with a track, a carriage movable along the track and provided, at its rear end, with two upwardly-projecting arms or members 27 arranged a suitable distance apart laterally, which carriage comprises a platform having upwardly-projecting 55 parallel flanges extending longitudinally of the platform and spaced laterally, and means for propelling the carriage along the track, of a rack employed in unloading ware onto the aforesaid platform from over the track, 60 which rack has a ware-receiving seat slotted to accommodate the location of the aforesaid flanges, with the different portions of the seat connected, at the rear of the seat, by a web which is slotted to accommodate the location 70 of the aforesaid arms.

27. The combination, with a track, a carriage movable along the track and comprising a platform having upwardly-projecting parallel flanges extending longitudinally of the 75 platform and spaced laterally, and means for propelling the carriage along the track, of a rack employed in unloading ware onto the aforesaid platform from over the track, which rack has a ware-receiving seat slotted to accommodate the location of the aforesaid flanges, with the different portions of the seat connected, at the rear of the seat, by a web, and the aforesaid carriage being provided with upwardly-projecting means 80 arranged to remove ware from the aforesaid seat during the actuation of the carriage, and the aforesaid web being slotted to accommodate the location of the ware-removing means 85 of the carriage.

Signed by us at Cleveland, Ohio, in the presence of two witnesses.
